IGNITION DISTRIBUTOR, ENGINE GOVERNOR, TACHOMETER DRIVE UNIT

Eugene C. Betttoni, Birmingham, Mich., assignor to Holley Carburetor Company, Van Dyke, Mich., a corporation of Michigan

Application January 28, 1957, Serial No. 636,824

9 Claims. (Cl. 123—97)

The present invention relates to an ignition distributor, engine governor, tachometer drive unit.

It is an object of the present invention to provide a novel arrangement of parts in an ignition distributor, engine governor, and tachometer drive unit which facilitates assembly and avoids difficulties previously encountered in connecting a tachometer to the ignition distributor.

More specifically, it is an object of the present invention to provide the elements of a combined ignition distributor and tachometer drive assembly so as to permit complete sub-assembly of elements with the drive shaft followed by insertion of the sub-assembly as a unit into the open end of the distributor housing.

Other objects and features of the invention will become apparent as the description proceeds, especially when taken in conjunction with the accompanying drawings, illustrating preferred embodiments of the invention, wherein:

Figure 1 is an enlarged side elevational view of the unit with parts removed and parts broken away.

Figure 2 is a fragmentary elevational view of parts of the assembly taken at 90 degrees from the view of Figure 1.

Figure 3 is a fragmentary sectional view at the shank end of the housing.

Figure 4 is a view similar to Figure 3 showing a modified construction.

The present invention is an improvement over the construction illustrated in my prior copending application Serial No. 591,168 filed June 13, 1956, now Patent Number 2,838,029.

The invention is illustrated in connection with an ignition distributor of the type having a distributor governor advance mechanism associated therewith and also including an engine governor mechanism. The details of the distributor governor advance mechanism and the engine governor manifold will not be described except to call attention to the fact that both include means actuated by fluid pressure.

The present invention has as its principal aim a design of structure which permits efficient inclusion of means for effecting tachometer drive with a minimum of difficulty and without requiring separate attachments, take-offs, etc.

The distributor housing 10 is completely open at its top as indicated at 12, and is substantially closed at its lower end, the lower end being provided with a generally cylindrical vertically extending recess 14. Adjacent the lower portion of the recess 14 it is provided with a lateral extension 16 providing space for the reception of a driven tachometer gear element indicated at 18. Below the recess 14 the housing 10 terminates in a reduced shank 20 having an opening 22 extending therethrough of a size only sufficiently large to receive the drive shaft together with the requisite seals.

The drive shaft is indicated at 24 and is adapted to be connected at its lower end to suitable driving mech-

2

anism such for example as gearing connecting it to the cam shaft or other rotating part of the engine. The drive shaft, which is indicated generally at 24, is actually composed of a lower section 24a and an upper section 24b for a purpose which will subsequently be described.

The housing 10 adjacent its upper end is provided with a flange 26 for the reception of a plate on which may be mounted conventional distributor mechanism not illustrated herein. It may be noted however, that the distributor mechanism includes means adapted to be actuated by a cam and the present construction includes means for adjusting the cam angularly with respect to the drive shaft 24. This mechanism is indicated at 28 and for the present it is sufficient to note that it includes a flexible diaphragm 30 adapted to be moved as a result of the differential between manifold vacuum and spring means indicated at 32. In general, it may be mentioned that the diaphragm is carried by a centrifugal element 34 movable outwardly by centrifugal force against a spring 36 to a position determined by engine speed. The flexible diaphragm 30 is movable relative to the centrifugal element and by suitable mechanism not pertinent herein, effects operation of a pin 38. Centrifugal means are provided at diametrically opposite sides of the shaft 24 and the two pins 38 move in unison in a direction tangential to a circle concentric with the shaft 24. The pins 38 are received in slots in actuating arms connected to a cam angularly movable on the shaft 24 and accordingly, the cam is advanced or retarded in accordance with engine speed and manifold vacuum. For a detailed description of this mechanism reference is made to the copending application of Kalin S. Johnson, Serial No. 592,000, filed June 18, 1956 and assigned to the assignee herein.

It will be observed that the distributor governor advance mechanism includes a tubular element 40 which extends through the shaft section 24b and which is in communication with a longitudinally extending passage 42 formed between shaft sections 24a and 24b.

The engine governor mechanism indicated generally at 43 includes a transversely extending tubular element 44 which extends through aligned openings in shaft sections 24a and 24b. The engine governor mechanism includes a passage 46 normally vented as indicated at 48 but adapted to be closed by a centrifugal weight 50 whose movement under centrifugal forces is opposed by a spring 52. The passage 46 communicates with a longitudinally extending passage 54 in the shaft section 24a.

The housing 10 is provided with an embossment 56 having fluid passages 58 and 60 extending to fitting receiving sockets 62 and 64. Received within the recess 14 is a shell housing 66 having annular grooves 68 and 70 communicating respectively with the passages 58 and 60. The grooves 68 and 70 in turn have radially extending ports 72 and 74 respectively opening to the interior of the shell housing 66. Received within the shell housing 66 are annular ported spacers 76 and 78 respectively in communication with the ports 72 and 74. At the inner surface of the annular spacers there are

provided annular grooves 80 and 82. The axially extending passage 54 in the shaft element 24a has a radial passage 84 communicating with the annular groove 82. In like manner, the fluid passage 42 provided between shaft members 24a and 24b communicates by a radial passage 86 with the annular groove 80. Annular spacers 76 and 78 are separated in the shell housing by a double seal 88 and annular seals 90 and 92 are provided at the top and bottom of the assembly respectively. The upper end of the shell housing 66 receives an upper bushing 94.

The shell housing 66 is in general of cup-shape and has at its lower end a transversely extending bottom wall 96 having an opening therein sufficiently large to receive

the shaft 24. The shell housing 66 has slight clearance with respect to the inner surface of the recess 14 and is provided with a plurality of O-ring seals indicated at 98.

Spaced slightly below the lower end of the shell housing 66 is the tachometer drive gear element 100 adapted to mesh with the driven gear 18. The tachometer drive element is keyed or otherwise fixed to the shaft 24 as indicated at 102. A seal 104 is provided below the gear 100 and within the shank of the housing.

The lower end of the shaft 24 may have a gear 106 keyed or otherwise secured thereto for connection to a part rotated in accordance with engine speed. If a gear such as 106 is secured to the lower end of the shaft, it will be apparent that it would not be attached until after the sub-assembly has been inserted in the housing 10. Preferably however, the lower end of the shaft 24 is provided with a coupling and driving formation whose cross-sectional area does not exceed that of the shaft. In Figure 4 such an arrangement is illustrated, the lower end of the shaft 24 being provided with a slot 108 which may receive a driving key carried by a driving element. In this case it will be observed that the shaft, the tachometer drive gear 100, the shell housing 66, together with the elements contained therein, the engine governor mechanism, and the distributor governor advance mechanism may all be removed as a unit from the housing 10 after the housing has been mounted on the engine. The parts may of course be replaced by simple insertion, taking care that the slot 108 registers with the driving key.

With the foregoing construction in mind it will be observed that the sub-assembly referred to is assembled by inserting the seals 92, the spacers 76 and 78, and the bushing 94 in the shell housing 66. The distributor governor advance mechanism 28 and the engine governor mechanism 43 are assembled on the shaft 24 and the shaft is inserted through the assembly of elements received within the shell housing 66. The tachometer drive gear 100 is next assembled on the lower end of the drive shaft and pinned in place with the necessary clearance between the bottom of the shell housing and the top of the gear.

This complete sub-assembly is adapted to be pressed into the distributor housing 10 with the shell housing 66 received in the recess 14 as illustrated, and retained therein by screws 110. If a gear of the type shown at 106 in Figure 3 is to be provided it may at this time be assembled on the lower end of the drive shaft 24 and suitably secured in place. If the gear 106 is omitted and the driving coupling is attached to the shaft 24 by engaging the slot 108 at its lower end with a driving key, it will of course be apparent that the complete assembly of elements illustrated as received within the housing 10 may be removed as a unit simply by removing the screws 110.

The drawings and the foregoing specification constitute a description of the improved ignition distributor, engine governor, tachometer drive unit, in such full, clear, concise and exact terms as to enable any person skilled in the art to practice the invention, the scope of which is indicated by the appended claims.

What I claim as my invention is:

1. A distributor and tachometer drive assembly comprising a housing open at the top and terminating at the bottom in a reduced pilot shank, said housing having a lateral enlargement adjacent its lower end for a driven gear element, a drive shaft having a tachometer drive gear fixed thereto insertable as a unit from the open upper end of the housing.

2. A distributor and tachometer drive assembly comprising a housing open at the top and terminating at the bottom in a reduced pilot shank having a opening therein only sufficiently large to receive a drive shaft, said housing having a lateral enlargement adjacent its lower end for a driven gear element, a drive shaft having a tachometer drive gear fixed thereto insertable as a unit from

the open upper end of the housing and having a portion fitting within and extending through the opening in said shank.

3. A combined distributor, governor and tachometer drive unit comprising a housing open at the top and having a reduced shank at the bottom provided with an opening only sufficiently large to receive a drive shaft, said housing having means at its upper end for mounting an ignition distributor, a sub-assembly comprising a cup-shaped shell housing having a substantially closed end provided with an opening therein, a shaft extending through the opening, said shaft having radially ported axially extending passages, a pair of radially ported annular spacers in the space between said shell housing and shaft, said shell housing having radial ports communicating with the ports of said spacers, a distributor governor advance mechanism connected to the upper end of said shaft including fluid pressure operated means in communication with one of the passages in said shaft, an engine governor mechanism connected to the upper end of said shaft and having fluid pressure operated means in communication with the other passage in said shaft, a tachometer drive gear fixed to said shaft below said shell housing, said sub-assembly being insertable as a unit through the open end of said housing with said shaft extending through the opening in the shank of said housing, said housing having passages communicating with the ports in said shell housing and having an enlargement for receiving a gear to be driven by said tachometer drive gear.

4. A combined distributor, governor and tachometer drive unit comprising a housing open at the top and having a reduced shank at the bottom provided with an opening only sufficiently large to receive a drive shaft, said housing having means at its upper end for mounting an ignition distributor, a sub-assembly comprising a cup-shaped shell housing having a substantially closed end provided with an opening therein, a shaft extending through the opening, said shaft having radially ported axially extending passages, a pair of radially ported annular spacers in the space between said shell housing and shaft, said shell housing having radial ports communicating with the ports of said spacers, a distributor governor advance mechanism connected to the upper end of said shaft including fluid pressure operated means in communication with one of the passages in said shaft, an engine governor mechanism connected to the upper end of said shaft and having fluid pressure operated means in communication with the other passage in said shaft, a tachometer drive gear fixed to said shaft below said shell housing, said sub-assembly being insertable as a unit through the open end of said housing with said shaft extending through the opening in the shank of said housing, said housing having passages communicating with the ports in said shell housing and having an enlargement for receiving a gear to be driven by said tachometer drive gear, the lower end of said shaft having a coupling formation no larger than the cross-section of said shaft whereby the complete sub-assembly may be removed from said housing as a unit.

5. In combination a housing open at its top and provided with an upwardly open recess in its lower end terminating in a reduced shank having an opening therethrough only large enough to receive a drive shaft, said recess having a lateral enlargement adapted to receive a driven tachometer gear, a sub-assembly adapted to be inserted in and removed from said housing as a unit, said sub-assembly comprising a shaft having radially ported axially extending fluid passages therein, a driving tachometer gear fixed thereto and dimensioned to be received in said recess, a cup-shaped shell housing having a bottom wall provided with an opening in which said shaft is received, a pair of ported annular spacers in said shell housing surrounding said shaft, and fluid actuated distributor, governor, advance mechanism and engine gov-

ernor mechanism fixed to said shaft above said shell housing and in communication with the passages therein.

6. In combination a housing open at its top and provided with an upwardly open recess in its lower end terminating in a reduced shank having an opening there-through only large enough to receive a drive shaft, said recess having a lateral enlargement adapted to receive a driven tachometer gear, a sub-assembly adapted to be inserted in and removed from said housing as a unit, said sub-assembly comprising a shaft having radially ported axially extending fluid passages therein, a driving tachometer gear fixed thereto and dimensioned to be received in said recess, a cup-shaped shell housing having a bottom wall provided with an opening in which said shaft is received, a pair of ported annular spacers in said shell housing surrounding said shaft, and fluid actuated distributor governor advance mechanism and engine governor mechanism fixed to said shaft above said shell housing and in communication with the passages therein, the lower end of said shaft having a coupling drive formation no larger than the cross-section of said shaft, whereby said entire sub-assembly may be removed as a unit from a mounted housing.

7. A distributor and tachometer drive assembly comprising a housing open at a receiving end and terminat-

5

ing at the other end in a reduced pilot shank, said housing having a centrally open portion for a driven gear element, a drive shaft having a tachometer drive gear fixed thereto insertable as a unit from the open receiving end of the housing.

10

8. A distributor and governor drive assembly comprising a housing open at a receiving end and terminating at the other end in a reduced pilot shank, drive shaft means having a distributor mechanism and a governor attached thereto insertable as a unit from the open receiving end of the housing.

15

9. A combined distributor, governor and tachometer drive unit comprising a housing open at a receiving end and terminating at the other end in a reduced pilot shank, said housing having a centrally open portion for a driven gear element, a drive gear having a tachometer and governor fixed thereto insertable as a unit from the open receiving end of the housing, with the tachometer drive being registerable with the driven gear element.
